COLOR IMPROVEMENT TREATMENT OF
DIALKYLAMIDES

William K. Wilkinson, Waynesboro, Va., assignor to E. I. du Pont de Nemours and Company, Wilmington, Del., a corporation of Delaware
No Drawing. Filed Dec. 11, 1963, Ser. No. 329,869
6 Claims. (Cl. 260—561)

This invention relates to a process for improving the color of dialkylamides. More particularly, it relates to the processing of impure dialkylamides for use as solvents in spinning operations.

In the spinning of spandex fibers and acrylonitrile fibers, it is common practice to use the lower dialkylamides of lower fatty acids, such as N,N-dimethylformamide and N,N-dimethylacetamide, as polymer solvents. These materials are good solvents for such polymers, and solutions thereof may be extruded or "dry spun" into filaments of high quality. Because of economic considerations, it is desirable to recover the evaporated solvent and reuse it. In practice, most of the solvent is recovered from the spinning cells by condensation from the aspiration gases, but since it has been subjected to relatively high temperatures during the spinning operation, it is contaminated with impurities.

Known purification processes for the dialkylamides involve distillation or deionization or both. It has been observed on occasion that such processes do not completely remove all impurities from the recovered solvent. In particular, the solvent retains either colored impurities or impurities which generate color on exposure to ultraviolet light. It is believed that these impurities include nitrosoamines which are formed during the spinning operation. As used herein, the term "UV color" refers to the color in the solvent after exposure to sunlight or intense ultraviolet light.

An object of this invention is provision of dialkylamide solvents substantially free of color and color-forming bodies and useful in the formation of polymer solutions and resulting yarns of improved color and quality. Another object of the invention is the purification of recovered dimethylacetamide solvent for use in spinning spandex fibers.

These and other objects are accomplished by a process of purifying a lower dialkylamide of a lower fatty acid which comprises treating the dialkylamide with hydrogen peroxide and distilling off impurities which boil at temperatures below that of said dialkylamide. In a preferred embodiment of this process, the pH of the dialkylamide is adjusted to at least 9.

The solvents which may be purified by the process of this invention are the lower dialkylamides of the lower fatty acids. These include dimethylformamide, diethylformamide, dimethylacetamide, dimethylpropionamide, and diethylacetamide. The essential step in the practice of this invention is the treatment of the recovered dialkylamide with hydrogen peroxide. The temperature and duration of the peroxide treatment is generally not critical, but ordinarily it should be for at least ten minutes at 155° C. The amount of hydrogen peroxide used should be in the range of from about 0.1% to about 5% by weight, based on the dialkylamide solvent being treated. Large amounts of peroxide are not necessary for the practice of this invention, and preferably the amount used is in the range from 0.1% to 0.5%, by weight. With dimethylacetamide, best results are obtained when using from 0.2% to 0.3% of hydrogen peroxide. Any convenient method of adding the peroxide may be used. The use of the commercially available 35% hydrogen peroxide in sufficient amounts to yield

the concentrations set forth above produces excellent results.

In the practice of this invention, it is necessary, for optimum results, to adjust the pH of the dialkylamide solvent to a value in the range from about 9 to about 11. Since the hydrogen peroxide is essentially neutral, the pH adjustment may be made before or after the hydrogen peroxide is added. If the pH of the dialkylamide is too low, it is brought into the proper range by the addition of a suitable basic material. Suitable materials include ammonium hydroxide and the lower dialkylamines. The preferred material is diethylamine which, in ordinary cases, is required in amounts ranging from about 0.1% to about 0.6%, by weight, based on the dialkylamide.

After treatment with the hydrogen peroxide at the specified pH, the treated dialkylamide is then stripped of low-boiling impurities by distillation. These impurities comprise, mainly, water and the dialkylamines, including dimethylamine, diethylamine, etc. In the distillation step, it is found to be beneficial if a substantial rate of purging the distillation column accompanies the distillation process. A purge rate of from about 10% to about 25% of the feed is found to be particularly helpful.

Although not essential for the practice of this invention, a heat treatment prior to the distillation step described above may advantageously be applied to the peroxide-treated dialkylamide. Thus, heating the peroxide-treated solvent to a temperature of about 155–160° C. for 10–15 minutes before distilling off the low-boiling impurities is particularly beneficial.

Further purification procedures known in the art may be carried out on the product from this invention, if desired. Thus, the residue from the above-described distillation may be subjected to a second distillation. In this subsequent distillation, the product is obtained as a distillate, preferably at a substantial reflux ratio, such as in the range from about 5:1 to about 6:1. Moreover, conventional deionization procedures may be applied to the product, if desired, whereby the solvent is passed through beds of cationic resins and beds of anionic resins, or alternatively, through a bed of mixed resins for further purification in accordance with the art.

The best method contemplated for carrying out this invention is as follows: the pH of condensed dimethylacetamide is adjusted to the range of 9–11 with diethylamine and is then mixed with sufficient aqueous 35% hydrogen peroxide to give a mixture containing from 0.1–0.5% peroxide. This mixture is fed continuously to a heater at 155–160° C. In the heater, the color-forming impurities are oxidized, and the organic peroxides which are formed are partially decomposed before being fed to a distillation column. The effluent from the heater is fed to a first column from which the low-boiling impurities are distilled off. The product is taken off at the base of the column and fed to a second distillation column from which it is distilled as a vapor, condensed, and passed through a column containing cationic and anionic resins to provide continuous deionization.

This invention is further illustrated, but is not intended to be limited, by the following examples in which parts and percentages are by weight unless otherwise specified. The color of the products is determined by electrophotometric measurement (using light of 425 millimicrons wavelength) and is reported herein as Hazen color numbers, which are the same as the widely used scale of the American Public Health Association. On this scale, distilled water is zero, and standard samples of stable inorganic salt solutions provide recognized calibration points. "UV color" is reported in Hazen numbers after exposure of a

3

50-ml. sample to a long-wave ultraviolet light source with maximum emission at 366 millimicrons wave length for four hours. The light source is a fluorescent light of two tubes with a power rating of 15 watts per tube. The sample is contained in a glass-stoppered bottle of soft glass.

Example I

The aspiration condensate containing about 2% water is obtained from a cell in which a spandex fiber is dry spun from a solution in dimethylacetamide. The pH of this condensate is adjusted to a level of 10 with diethylamine. Sufficient 35% hydrogen peroxide is then added to give a mixture containing 0.25% hydrogen peroxide. This mixture is heated for about 15 minutes to a temperature of 155-160° C. and is then fed to a distillation column from which water and other low-boiling impurities are distilled off. The dehydrated product is taken off at the base of the column as a vapor, condensed, and fed to a second distillation column from which it is distilled. The distillate is passed through a bed consisting of a mixture of "Amberlite"¹ resins IR-200 and IRA-400. The product has a color (Hazen number) of 0.3 and a "UV color" of 10.2.

Similar condensate, similarly processed except for deletion of the treatment with hydrogen peroxide and diethylamine, has a color of 0 and a "UV color" of 42.

Example II

Dimethylacetamide aspiration condensate, recovered from a spandex dry spinning process, is mixed with sufficient 35% hydrogen peroxide solution to give a mixture containing 2% hydrogen peroxide. The mixture is heated under reflux for approximately 25 minutes. Water and low-boiling impurities are then distilled off and discarded as a first fraction. A second fraction is distilled and collected at the boiling point of dimethylacetamide. This product has a color of 11 and a "UV color" of 14.

Similar condensate, processed in the same manner except for deletion of the treatment with hydrogen peroxide, has a color of 9 and a "UV color" of 192.

The process of this invention has the advantage over other purification procedures in that the decomposition products of hydrogen peroxide are water and oxygen which are easily removed from the treated dialkylamides on distillation. Moreover, under the conditions specified herein, the mixture of hydrogen peroxide and dialkylamide may be safely handled in a large-scale operation without danger of build-up of hazardous concentrations of organic peroxides. In addition, use of hydrogen

peroxide, particularly at low concentrations, avoids fouling of the calandria or heating elements of the distillation column by the oxidizing agent or its decomposition products.

5 It is not known with certainty what the color-forming
impurities in recovered dialkylamide are, but it is believed
10 that they are converted by the hydrogen peroxide to materials which are easily removed on distillation. Dialkylamides recovered from a spandex spinning process
10 and purified by the process of this invention are reusable in the preparation of spandex spinning solutions free of objectionable color.

As many widely different embodiments of this invention may be made without departing from the spirit and scope thereof, it is to be understood that this invention is not to be limited to the specific embodiments thereof except as defined in the appended claims.

I claim:

- 1 claim.

1. A process for treating a lower dialkylamide of a lower fatty acid to remove color-producing impurities which comprises adding from about 0.1% to about 5% by weight of hydrogen peroxide to said dialkylamide, distilling the hydrogen peroxide-containing mixture at a temperature below the boiling point of said dialkylamide, and thereafter collecting the dialkylamide.

2. The process of claim 1 wherein the pH of the dialkylamide is adjusted to a value from about 9 to about 11 before the mixture is distilled.

3. The process of claim 2 wherein the mixture is heated for a period of from about ten to fifteen minutes at a temperature from about 155° C. to 160° C. before the distillation step.

4. The process of claim 3 wherein said dialkylamide is dimethylacetamide.

5. The process of claim 3 wherein said mixture is fed to a distillation column using a purge rate of from about 10% to about 25%.

6. The process of claim 1 wherein said dialkylamide is the solvent recovered from a spinning operation.
